US00D887574S

(12) **United States Design Patent** (10) Patent No.: **US D887,574 S**
(45) Date of Patent: ** *Jun. 16, 2020

(54) **PIPETTE TIP FOR A LABORATORY INSTRUMENT**

(71) Applicant: **Beckman Coulter, Inc.**, Brea, CA (US)

(72) Inventors: **Takayuki Mizutani**, Edina, MN (US); **Shigeru Fujii**, Shizuoka (JP); **Kazuki Umebara**, Shizuoka (JP)

(73) Assignee: **BECKMAN COULTER, INC.**, Brea, CA (US)

(*) Notice: This patent is subject to a terminal disclaimer.

(**) Term: **15 Years**

(21) Appl. No.: **29/680,748**

(22) Filed: **Feb. 19, 2019**

Related U.S. Application Data

(63) Continuation of application No. 29/582,709, filed on Oct. 28, 2016, now Pat. No. Des. 841,182.

(57) **CLAIM**

The ornamental design for a pipette tip for a laboratory instrument, as shown and described.

DESCRIPTION

FIG. 1 is a perspective view of the pipette tip for a laboratory instrument;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a cross sectional view taken along line 8-8 shown in FIG. 6.

The dashed lines in the drawings represent portions of the pipette tip for a laboratory instrument that form no part of the claimed design.

1 Claim, 4 Drawing Sheets
